SHOESHINE DEVICE

Bert Gaither, Van Nuys, Calif.

Application December 1, 1951, Serial No. 259,430

2 Claims. (Cl. 15—265)

1

This invention relates to a shoeshine device more particularly adapted for use in the home.

An object of the present invention is to provide a device of the character indicated that, from a normal closed box-like condition, can be quickly converted to an open operative condition. In the former condition, the device serves to store shoe polishing articles and in the latter condition, the same serves as a stand to support the foot wearing the shoe to be shined.

Another object of the invention is to provide a shoeshine device that has a hinged top adapted to be propped in an elevated position so that the upper end of the same constitutes a foot rest and to provide a portion hinged on the hinged top and adapted to be thrown open to constitute a shelf or ledge to support shoe polishing articles within easy access of the person using the device.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes one embodiment of the present invention, which is given by way of illustration or example only.

In the drawing, like reference characters designate similar parts in the several views.

Fig. 1 is a perspective view of a shoeshine device according to the present invention, the same being shown in closed condition.

Fig. 2 is a longitudinal sectional view of said device in open operative condition.

The improved shoeshine device that is illustrated comprises, generally, a box 5 comprised of a base 6 and a cover 7 connected to said base by a hinge 8 at one end, a shoe rest 9 that also comprises a carrying handle for the box and mounted on the top of cover 7, a shelf or ledge 10 carried by said cover and movable on hinges 11 between a position closing the box and forming part of cover 7 and an open position constituting an article-supporting shelf, a prop element 12 swingably engaged with box base 6 and movable between a position enclosing the contents of said base and an elevated position propping open said cover so that the uppermost portion 13 of the latter constitutes a foot-supporting portion.

The box 5 is advantageously made of wood or

2

like material and, in general, is rectangular in form with the hinge 8 at one end. The base 6 preferably has substantial depth to provide ample space for storing brushes, polish cloths, polish, etc., therein. Cover 7 may be relatively shallower than the base, substantially as shown.

Shoe rest 9 is an auxiliary element. However, the same serves as a handle for the box. Since it has the function of a shoe rest, element 9 is preferably provided on its upper outer surface with a lining 14 of cork or like material and said element is preferably sloped as shown so that it may be conveniently used from a sitting position.

Member 10 comprises a panel which, in closed condition, completes the top of cover 7, as shown in Fig. 1. Element 9 is mounted on said panel and the latter is held in closed position by catches 15 on both sides. Said catches are carried by the sides of box base 6 and, when holding panel 10 closed, also holds closed cover 7. In this way, separate catches for the cover are not needed and are, therefore, omitted.

The shelf panel 10 is supported at its free end by a cleat 16 and the portion thereof adjacent hinge 11 cooperates with a transverse wall 17 to prevent displacement of articles supported on said shelf when in operative position. Between cleat 16 and wall 17 is defined an opening 18 through cover 7, the same affording ready access to the interior of the base 6 when the device is arranged in operative position.

The element 12, in its simplest form, comprises a rectangular board or panel of a size to quite loosely fit into the top of box base 6. In the present case, said element is hingedly connected at one end 19 to the base on the end of the base opposite to hinge 8, and, at the other end, is supported by a lug 20. A hole 21 in panel 12 facilitates upwardly swinging the same on its hinged end 19. A piece of dowling may serve as hinge 19, the ends of the same being entered in openings provided in the sides of base 6. The primary purpose of member 12 is its use as a prop for cover 7. Fig. 2 shows such arrangement wherein the free end of the prop panel is engaged with the recess 22 that is formed by a cleat 23 provided across the free end of cover 7.

In the above manner, a triangular support for foot rest 13 at the end of cover 7 is provided, the support, thereby, having non-interfering relation to the hands of the user particularly when reciprocating a polishing cloth across a shoe supported by rest 13. Moreover, the foot rest 13 is brought to a relatively elevated position so that the shoe-polishing operation may be carried out

in a quite comfortable standing position. In this operative position of the device, the shelf panel 10 is thrown open and is supported by handle element 9, as shown, to comprise an article-supporting means.

As illustrated in Fig. 2, height adjustment of foot rest 13 may be embodied in the device by providing for selective high or low position of hinge 19. To this end, an upper support 24 is provided in side plates 25 in base 6, the lower support comprising the base bottom 26. A slot 27 in each plate 25 allows for adjustable movement of hinge 19 between said two supports. One or more intermediate supports, similar to support 24 may be provided to adjust the elevated position of foot rest 13 as desired.

Since foot rest 13 is above base 6 and between the ends thereof, the device is quite stable in any adjusted operative position. Said foot rest 13 is lined as at 28 with cork or the like to provide a non-slipping rest. Shelf 10, because of its more elevated position than base 6, adds to the facility of use of the device. Elastic strap 29 is under tension when cover 7 is raised since the same is connected between said cover and the base. Accordingly, assurance is had that the cover will, at all times, seek interlocking engagement with the free end of prop element 12. Said strap 29 limits the rearward position of cover 7 and it will be evident that any suitable folding brace may be employed for this purpose.

While the invention that has been illustrated and described is now regarded as the preferred embodiment, the construction is, of course, subject to modifications without departing from the spirit and scope of the invention. It is therefore not desired to restrict the invention to the particular form of construction illustrated and described, but to cover all modifications that may fall within the scope of the appended claims.

Having thus described the invention, what is claimed and desired to be secured by Letters Patent is:

1. A shoeshine device comprising a flat, rectangular and relatively shallow open-topped base

10
5
10
15

adapted to store shoe-shining paraphernalia, a generally flat rectangular cover hinged at one end to said base and movable on its hinge between a position to cover the open top of the base and an elevated position extending at an upward angle with respect to the base, the free edge of said cover constituting a foot rest when the same is elevated, a rectangular member pivotally engaged with the base adjacent the end thereof opposite the end having the cover hinge, said pivotal engagement comprising lateral trunnions on said member and vertically spaced pivotal and selective supports for said trunnions and adapting said member to be swung between a flat position closing the open top of the base, when the trunnions are supported by the upper of said supports, and an upwardly angular position having its free end in prop-supporting engagement with the free end of the cover, when said trunnions are supported by either of said supports, selectively, and a lug in the base and opposite to and aligned with the upper of the vertically spaced supports to support the free end of said member when positioned to close the top of the base.

2. A shoeshine device according to claim 1; said cover and prop member, when in engagement, comprising a triangular structure overstanding the base, the cover having an opening therein, and a hinged handle member normally closing said opening and adapted to be swung outward to expose said opening and, thereby, give access to the interior of the base through said overstanding structure.

BERT GAITHER.
